UNITED STATES PATENT OFFICE.

VERNON ROYLE, OF PATERSON, NEW JERSEY.

MACHINE FOR PUNCHING JACQUARD-CARDS.

SPECIFICATION forming part of Letters Patent No. 644,871, dated March 6, 1900.

Application filed August 14, 1898. Serial No. 602,755. (No model.)

To all whom it may concern:

Be it known that I, VERNON ROYLE, of Paterson, in the county of Passaic and State of New Jersey, have invented a new and useful 5 Improvement in Piano-Machines for Punching Jacquard-Cards, of which the following is a specification.

My invention relates to an improvement in piano-machines for punching jacquard-cards, 10 and more particularly to that type of machine which is known in the art as a "power-machine" as distinguished from a machine driven by the operator.

In the accompanying drawings, Figure 1 is 15 a view of the machine in front elevation. Fig. 2 is a top plan view with pattern-support broken away. Fig. 3 is a side elevation, the side of the supporting frame or pedestal being removed to show the operating parts more 20 clearly. Figs. 4 and 5 represent views in detail of the clutching mechanism in released and locked positions, respectively. Fig. 6 is a view in detail of a portion of the feed-carriage support, showing the feed-carriage and 25 its connection with the support. Fig. 7 is a view in detail of the dogs for controlling the movement of the carriage, showing them in position upon their rock-shaft support. Fig. 8 is an enlarged vertical section in detail 30 through the segment and its operating mechanism for raising and lowering the rule on the pattern-board. Fig. 9 is a top plan view of the same. Fig. 10 is an enlarged vertical section through the feed-carriage-operating 35 shaft and the parts carried thereby. Fig. 11 is an enlarged plan view, partly in section, in detail, of the spring-actuated wheel for returning the index-finger across the pattern-board. Fig. 12 is a partial vertical section 40 of the machine, taken at right angles to the plane of Fig. 4. Fig. 13 is a horizontal section through the carriage, taken on an enlarged scale through the plane of the teeth of the rack-bar, showing the parts below in top plan.

45 Figs. 14 and 15 are partial end views of the carriage, showing the two positions which the rocking teeth for engaging the rack-bar assume when their operating-shaft is swung to the limit of its rocking movement in each of 50 two opposite directions. Fig. 16 is a horizontal section taken beneath the table a^2 , and

Fig. 17 is a bottom plan view of the apron a^3 and the parts carried thereby.

The machine comprises an operating wheel or pulley, which may be driven from a suitable source of power, a punching mechanism, an operating-shaft connected with the punching mechanism, means under the control of the operator for locking the operating-shaft to and releasing it from the continuously-driven 55 pulley at pleasure, a feed mechanism under the control of the punching operating mechanism to feed the card at the desired intervals, a pattern-support mounted to assume such varying positions as may be desired and 60 provided with means for determining at each step the exact position of the particular point in the pattern which is to be considered in punching the card, and in connection with the above-mentioned features several specific features of structure and arrangement, as will be hereinafter particularly described.

The pedestal or main supporting-frame consists of side plates $A A'$, connected by a web a and made flaring at the base. The pedestal is supported upon yielding cushions—such, for example, as rubber—(denoted by a') and at its top is provided with a table a^2 , from which an apron a^3 projects toward the front.

A punching mechanism of any well-known 80 or approved form is shown at B. It is supported by a pair of guide-rods $b b'$, which extend down through the table a^2 and into sockets formed in lugs $a^4 a^5$ at the base of the pedestal. The guide-rods $b b'$ are connected 85 by a cross-piece b^2 , which is connected by an eccentric-rod b^3 with an eccentric c on the drive-shaft C to impart to the punches the reciprocating movement when the shaft is rotated.

The drive-shaft C is mounted in an extended bearing a^6 , projecting rearwardly from the pedestal, and the continuously-driven pulley D for actuating the machine is mounted on the rear end of the shaft. The shaft C is 95 clutched to and released from the pulley D as follows: Fixed to rotate with the shaft C are clutching-shoes $E E'$, placed in the present instance diametrically opposite one another and attached to their supporting-wings $e e'$ by stems e^3 , (two for each shoe,) which permit the shoes to slide radially toward and

away from the inner curved surface of the rim d of the pulley D. The shoes are connected with a hub e^6 , mounted to rock independently of the wings e e' , by what I am pleased to call "toggle-dogs" e^4 e^5 . Arms e^7 and e^8 radiate from the hub e^6 and have their free ends connected by springs e^9 e^{10} with fixed supports on the wings e e' , the tension of the springs being such that when free to act they 10 will rock the hub e^6 in a direction to throw the toggle-dogs into or toward the radial lines from the position shown in Fig. 4 to the position shown in Fig. 5 to press the shoes E E' simultaneously toward the rim of the pulley 15 to clutch the shaft thereto. The hub e^6 is positively rotated in the opposite direction to release the shoes from the pulley by means of an arm e^{11} , which is operated by a nose or cam F, fixed to rock with a dog f, which is 20 operated by a cam f' on a sleeve f'', mounted to slide longitudinally on the shaft C. The free end of the arm e^{11} is connected by a spring e^{12} with the tail of the dog f. The sleeve f'' is slid along the shaft C to operate and release 25 the clutch by means of a pair of foot-levers G G', fulcrumed on a hanger g, depending from the bearing a^6 and connected by rods g^1 g^2 with two oppositely-extending arms g^3 g^4 of a tri-armed lever, the third arm g^5 of which has 30 its free end engaged with the said sleeve f''. The levers G and G' are provided with adjustable stops g^6 g^7 to limit their downward movements. In operation when the lever G' is depressed, as shown in Fig. 3, the sleeve f'' will be slid toward the front to bring the cam f' out of the path of the dog f, and the shoes E E' will thereby be left free to clutch the pulley D to the shaft; but when the lever G is depressed the sleeve f'' will be slid into 35 position to place the cam f' in the path of the dog f and it will be rocked into the position shown in Fig. 4, thereby forcing the hub e^6 around against the tension of the springs e^9 e^{10} and releasing the clutching-shoes, and 40 hence the shaft C, from the pulley.

The card is fed rearwardly step by step alternately with the operation of the punches as follows: A guide-bar H, forming a support and track for the feed-carriage I, projects rearwardly from the pedestal below the apron a^3 . In the present instance the bar H is cylindrical in cross-section and has fixed in its under side a rack-bar h. The body of the carriage I is simply a short sleeve fitted 45 to slide smoothly along the bar H and provided with two pairs of uprising legs i i' and with depending legs i^2 i^3 , which embrace a rock-shaft K, extending parallel with and spaced a short distance from the supporting- 50 bar H. On the rock-shaft K, between the legs i^2 and i^3 of the feed-carriage, there are located two short sleeves or collars k k', the former, k, fixed to the shaft K and the latter, k', caused, by means of the well-known 55 feather-and-groove attachment or its equivalent, to rock with the shaft, but permitted to move a limited distance back and forth 60

longitudinally of the shaft. The distance the part k' is permitted to move is regulated by a nut k^2 on a screw-threaded extension of the part k', which causes the said part to be stopped by the leg i^3 earlier or later, according to the position of the nut. 70

The sleeves or collars k k' are each provided with a tooth, the former with a tooth k^3 and the latter with a tooth k^4 , located in different longitudinal planes through the axis of the shaft K, so that when one of the teeth is swung into position between two teeth of the rack-bar h the other will be out of engagement with the rack-bar. The collar or sleeve k' is held normally to the limit of its movement away from the part k by means of springs k^5 , inserted in sockets in the face of the part k' and bearing against the face of the part k. 80

The shaft K is rocked to bring first one and then the other of the teeth k^3 k^4 into engagement with the rack-bar by an angle-lever having a socket portion L for the reception 90 of the end of the shaft at the front of the machine, one arm l being pivoted to a sleeve l'' on a rod l', connected with an eccentric l'' on the drive-shaft C, and the other arm l' being connected by a rod l'' with a crank-arm 95 l'' on an operating-rod l', provided with a handle l'' within convenient reach of the operator at the front of the machine. The sleeve l'' is connected with the rod l'' by a spring l'', the tension of which is sufficient to cause the 100 sleeve to reciprocate with the rod l'' to rock the shaft K, but permitting the shaft K to be rocked by hand by the rotation of the operating-rod l' without disturbing the rod l'', connected with the eccentric. 105

The feed-carriage is drawn constantly to the rear by means of a spring-actuated pulley M, to the periphery of which the ends of a cord m are secured, the bight of the cord passing about one of a vertical series of pulleys m', mounted on the upright arm m'' of an angle-lever pivoted at m'' to the carriage and having its forwardly-extending arm m''' loosely engaged with the tail of a gripping-dog m'', pivoted to the carriage at m''', with its gripping-jaw m'' in position to hold the rear end of the card being operated upon between it and a stationary jaw m'' at the front of the carriage. For relieving the sliding friction on the bar H, the carriage may be provided 110 with rollers i'' i''', set in position to sustain the weight of the carriage on the bar, the rollers i'' being set obliquely at the front of the carriage in a pair and the roller i''' being set upright in position to travel along the crown of 115 the bar. 120

The grip of the dog m'' upon the card may be increased or diminished, while the spring tension remains the same, by shifting the bight of the cord m to an upper or lower pulley of the series m'. 130

The pulley M is fixed to a shaft N, mounted in the branches of the bifurcated head O, fixed to the rear end of the bar H. The shaft

N is held under spring tension by a pair of coiled springs $n^1 n^2$, located upon opposite sides of the shaft-bearings and having one end of each connected to a cross-bar o, fixed 5 to the head O, and the opposite ends to the shaft N, or, as preferred, to sleeves n^3 , mounted on the shaft N within the spring-coil and fixed to hand-wheels n^4 , which may be locked to the shaft N by means of disks n^5 , the hubs 10 of which are connected with the shaft N by the ordinary feather-and-groove or other equivalent means, the said hand-wheels n^4 being forced into frictional gripping-contact with the disk n^5 by hand-nuts n^6 , which work on 15 screw-threaded portions of the shaft N and bear against movable disks n^7 on the shaft at the opposite ends of the sleeves n^3 from the hand-wheels n^4 . This structure admits of releasing the hand-wheel of either spring from 20 the shaft N at pleasure and then winding or unwinding the spring by turning the hand-wheel in one direction or the other to get just the most efficient amount of tension on the carriage to cause the escapement hereinabove 25 particularly described to work to the best advantage. The feed-carriage is provided at its rear end with a plunger i^1 , which as the carriage nears the limit of its rearward movement enters a socket o' in the head O and 30 forms a compressed-air cushion, particularly when the carriage is permitted from any cause to travel back quickly to prevent injury from sudden stoppage.

The cards as they are drawn rearwardly by 35 the carriage are supported upon wires $o^2 o^3$, leading from the opposite wings of a pivoted bracket o^4 on the head O forwardly to the rear edge of the apron a^3 .

A pair of laterally-sliding cheek-pieces P 40 P' are automatically drawn toward each other by link connections $p^1 p^2$, with the opposite arms $p^3 p^4$ of a lever pivoted to the table a^3 at p^4 , the arm p^3 of the lever being connected with the table by a spring p^5 , which may be 45 attached to the lever at different distances from its fulcrum to exert a greater or less tension upon the cheek-pieces. The limit of the movement of the cheek-pieces toward each other is determined by a pin p^6 on a 50 slide p^7 , which may be adjusted laterally of the table by a set-screw p^8 , thereby rendering it feasible to adjust the cheek-pieces to cards of different widths without changing the position of the center line between the 55 pieces and leaving the pieces at all times free to be separated to insert a card.

The feed-carriage has attached thereto a cord i^2 for drawing it forward into position to grip the end of a card. The same cord i^2 60 passes over a pulley p^9 on the cheek-piece P, so that the strain upon the cord to pull the carriage forward may be utilized to draw the cheek-pieces apart for the insertion of a blank card between them.

65 As the shaft C rotates to operate the punches it rocks the shaft K over and back to bring the ratchet-teeth $k^3 k^4$ into and out

of engagement with the rack. Suppose the feed-carriage to be under strain from its actuating-pulley as the tooth k^3 is rocked out 70 of engagement with the rack and the tooth k^4 into engagement therewith. The feed-carriage, together with the tooth k^3 , will move rearward against the tension of the springs k^5 until the sleeve or collar k, carrying the 75 tooth k^3 , abuts against the sleeve or collar k', carrying the tooth k^4 , at which point it will be arrested by the engagement of the tooth k^4 with the rack on the bar H. When the shaft K is rocked back, the tooth k^3 will engage the rack at a point farther to the rear, and as soon as the tooth k^4 escapes from the 80 rack it will jump rearward under the tension of the springs k^5 into position to again arrest the rearward movement of the carriage 85 when the tooth k^3 is released. When the card has been punched and it is desired to return the feed-carriage to the front, the rod l^1 is turned by the hand of the operator, thereby rocking the shaft K sufficiently to 90 throw the teeth $k^3 k^4$ out of engagement with the rack h, and the carriage is then drawn directly to the front by the cord i^2 . The spring l^2 , connected with the sleeve l^3 , will 95 serve to rock the shaft K to bring the teeth $k^3 k^4$ into the proper relation to the rack as soon as the handle l^4 is released.

The pattern which furnishes a guide to the operator in punching the cards is held spread before him on the face of a pattern-board 100 Q. The board Q is provided with a pair of supporting-brackets $q^1 q^2$, fixed to its back and hinged at their lower ends, as at q^3 , to a base-plate q^4 to permit the board to be tilted forward and backward to assume the 105 slant which is found most expedient for reaching the pattern. The board is adjusted in its various tilting or in its upright positions by means of a slotted link or brace q^5 , pivoted at its upper end to the bracket q^2 110 and receiving through the slot in its lower end a set-screw q^6 for clamping it to the plate q^4 . The base-plate q^4 is fixed in forward and backward adjustment on the tops 115 of a pair of standards $q^7 q^8$ by means of bolts q^9 , which extend through elongated slots q^8 into the heads of the standards. The standards $q^7 q^8$ are bolted at their bases to the top of the pedestal A A'. The board Q may also be bodily raised and lowered by means of the 120 several half-sockets q^{10} , arranged in different vertical positions and each adapted to receive the pintle of the hinge at q^3 .

A double rule, consisting of the parallel bars R R', fixed to end pieces $r r'$, is attached 125 to the pattern-board in vertically-sliding adjustment, in the present instance by fitting the ends $r r'$ to slide on ways r^2 at the ends of the board. The rule is adjusted by means of a cord or wire attached to the ends of the 130 rule and operated to simultaneously move the said ends in the same direction, as follows: A supporting-bracket S is fixed to the rear lower central portion of the board and

- carries a short vertical axle s , on which is mounted a worm-wheel s' , the hub s^2 of which has mounted thereon a segment s^3 , provided with an operating-lever s^4 . The worm-wheel s is held in longitudinal adjustment on the axle s by means of a key or nut s^5 , and the hub s^2 is screw-threaded to receive an adjusting-nut s^6 , preferably made large enough to be grasped and operated by the hand, which nut bears against the hub of the segment s^3 and serves to lock it to and release it from the worm-wheel, as may be desired. The worm-wheel s' is operated by a worm s^7 on a shaft s^8 , provided with a hand-wheel s^9 for turning the shaft, and hence the worm and worm-wheel, to operate the segment when the latter is locked to the worm-wheel.
- The segment is provided with a pair of angle-levers $s^{10} s^{11}$, one on each side, fulcrumed on the segment and having their longer arms connected by a spring s^{12} and their shorter arms each connected with one end of the rule-operating wire T . The spring s^{12} serves to take up slack in the wire and hold it under a limited tension, while the full tension is increased or diminished by means of screws $s^{13} s^{14}$, which extend through elongated slots in the levers $s^{10} s^{11}$ and engage screw-threaded sockets in bosses $s^{15} s^{16}$, projecting from the hub of the segment. From the short arm of one of the levers—for example, s^{10} —the wire T extends across the curved face of the segment and thence to a guide-pulley r^3 at the lower portion of one of the ends of the board, thence up along the end of the board where it is attached to the end r' of the rule, thence over a guide-pulley r^4 at the top of the board, thence down and around a guide-pulley r^5 , here shown as concentric with the guide-pulley r^3 , thence along the lower portion of the board to a guide-pulley r^6 at the opposite end of the board, thence up along the end of the board where it is attached to the end r of the rule, thence over a guide-pulley r^7 at the top of the board, thence down around a pulley r^8 , here shown as concentric with the pulley r^6 , and thence across the curved face of the segment s^3 to the short arm of the opposite lever s^{11} , to which it is attached. When it is desired to set the rule to read any line of the pattern, the rule may be quickly raised or lowered to a point near its desired position by releasing the segment from the worm-wheel and turning it directly by its lever, and the adjustment may be completed to a hair's breadth of exactness by then locking the segment to the worm-wheel and completing its movement by operating the worm s^7 .
- The above will suffice for keeping the eye of the operator on the horizontal line of the pattern; but it is also found desirable to keep the attention directed to the particular cross-thread at each step of the punching. I provide for this by causing a pointer to travel across the pattern step by step under the control of the feed mechanism, as follows: At or

near one end of the pattern-board there is mounted a vertical shaft U in bearings projecting rearwardly from the board, and on a squared portion of the shaft U there are located two disks $u u'$, of equal periphery and preferably a distance apart corresponding to the distance between the two parts $R R'$ of the double rule. The disks $u u'$ are caused to slide up and down with the rule by means of a bracket U' . A cord V , secured at one end to the face of the disk u , extends across the face of the board Q to the periphery of a spring-actuated wheel W at the opposite end of the board, also arranged to move up and down with the rule, and is wound around the said wheel a sufficient number of turns or fractional part of a turn to permit the cord to be drawn from the wheel a length sufficient to traverse the pattern. In a similar manner a second cord V' is secured at one end to the face of the disk u' and extends thence across the face of the board Q to and about a guide-pulley W' at the opposite end of the board and thence up and around the periphery of the wheel W in the same direction as that in which the cord V passes around it, so that both cords may be simultaneously drawn with equal speeds from the wheel W by the rotation of the disks $u u'$. An index-finger v , which may consist of an ordinary pin or needle, may be placed in engagement with either of the cords at the point where the reading of the pattern is to begin. The wheel W may be actuated by an ordinary coil-spring w , connected at one end with a fixed pin w' and at its opposite end with the hub w^2 of a hand-wheel w^3 , mounted on the axle w^4 , on which the wheel W rotates. The hand-wheel w^3 is locked to the hub of the wheel W by means of a nut w^5 , screwed on the end of the axle w^4 , which serves to crowd the hand-wheel into frictional engagement with the wheel W to bring the latter under the tension of the spring w or to release the hand-wheel from the wheel W to permit the spring to be wound or unwound independently of the wheel W . The shaft U is further provided with a pulley u^2 , fixed thereon, the periphery of which is connected by a cord u^3 , extending from the pulley u^2 around a guide-pulley u^4 , with a drive-pulley u^5 on the spring-actuated shaft N , which as the feed-carriage I moves to the rear step by step winds the cord u^3 on its periphery, and thereby rotates the shaft U and disks $u u'$ thereon to draw the index-finger v on either of the cords $V V'$ step by step across the pattern, at the same time winding the spring which actuates the wheel W , so that when the feed-carriage is returned to the front and the cord u^3 unwound from the pulley u^5 the wheel W , under the tension of its actuating-spring, will wind the cords $V V'$ on its periphery and return the index-finger to position.

The length of the step which the index-finger travels may be varied to suit patterns having the cross-lines at different distances

apart by changing the drive-pulley v^5 for others of greater or less diameter, the pulley v^5 being for this purpose made readily removable from the shaft N in any well-known or 5 approved manner.

For indicating to the operator the position of the card where each punching operation takes place on the card being punched, I lead a cord V^2 from the front of the carriage to and 10 around pulleys V^3 V^4 at the front of the pattern-board and provide the opposite end of the said cord with a weight V^5 for keeping the cord taut and causing it to travel over the pulleys V^3 V^4 when the carriage is returned. 15 On this cord an index needle or finger of any well-known or approved form may be placed in such a manner as to travel along a sample card (not shown) placed at the bottom of the board in front of the operator and having 20 thereon the full number of transverse lines of perforations which the card will contain. In operation, at each punching operation the index-finger will be moved by the movement of the carriage a step from one transverse line 25 of perforations on the card to the next, and hence give the desired information.

Boxes X and X' are located at the right and left of the table a^3 as the operator faces the machine for receiving the blank cards and the 30 punched cards, respectively.

In the foregoing description I have referred to the shaft N as spring-actuated, and in practice I prefer to use a spring in connection with the special means for regulating its 35 tension; but I wish to be understood in using the term "a spring-actuated" to include the use of a weight, which in many instances is considered, generically, the equivalent of a spring and which may obviously be utilized in my 40 present structure without requiring any considerable modification.

The clutch mechanism herein above described is introduced and claimed in the present application only in connection with the 45 parts of the punching mechanism which intimately coact therewith, the said clutch mechanism *per se* forming the subject-matter of another application, Serial No. 740,907.

What I claim is—

50 1. In combination, punches, keys for controlling the punches, said keys being arranged for operation by the hands of the operator, a drive-shaft for operating the punches, a drive-wheel loosely mounted on the drive-shaft, a clutch for locking the drive-wheel to and releasing it from the shaft, clutch-operating mechanism arranged to move along the drive-shaft into and out of operative position and interconnected foot-pedals connected with the 55 clutch-operating mechanism one for throwing the clutch-operating mechanism into operative position and the other for throwing the clutch-operating mechanism out of operative position, substantially as set forth.

60 2. In combination, a punching mechanism, means for operating it, a feed-carriage, a bar forming a support for the carriage, means for

drawing the carriage along the bar, a rack fixed to the carriage-supporting bar, a rock-shaft, teeth carried by the rock-shaft in position to alternately engage the rack as the shaft rocks, while free to move along the shaft, said carriage being engaged with said teeth to move along its support as the teeth move along the shaft and means for rocking the shaft to permit the carriage to move step by step, substantially as set forth. 70

3. The feed mechanism comprising a feed-carriage, a supporting-bar along which the carriage is adapted to travel, a rack fixed to 80 said bar, a rock-shaft, independent teeth mounted to rock with the shaft and free to slide along the shaft, a spring tending to slide one of the teeth away from the other, the aforesaid carriage being provided with abutments for holding it engaged with the teeth, means for rocking the shaft to bring the teeth alternately into engagement with the rack and means for keeping the carriage under tension tending to draw it along its support, substantially as set forth. 85

4. The combination with the feed-carriage, its actuating-spring and means for controlling its movement, of a pivoted jaw mounted on the carriage for engaging the card and a 95 rocking lever having one arm loosely engaged with said pivoted jaw and another arm connected with the carriage-actuating spring, substantially as set forth.

5. The combination with the feed-carriage, 100 its actuating-spring and means for controlling its movement, of a pivoted jaw mounted on the carriage for engaging the card and a rocking lever engaged with said pivoted jaw and provided with a series of bearings for 105 attaching it to the carriage-actuating spring at different distances from its fulcrum, substantially as set forth.

6. The combination with the feed-carriage, 110 its operating-spring, the rack, the rock-shaft and the teeth carried by the rock-shaft, of a lever for rocking the shaft, a shaft-operating rod having a yielding connection with one arm of the lever, a hand operating-rod and a connection between the hand operating-rod 115 and the said lever for rocking the shaft to release the teeth from the rack for returning the feed-carriage, substantially as set forth.

7. The combination with the feed-carriage, 120 its operating-spring, the rack, the rock-shaft and the teeth carried by the rock-shaft, of the angle-lever for rocking the shaft, the shaft-operating rod having a yielding connection with one arm of the angle-lever, a hand operating-rod and a connection between the hand 125 operating-rod and the said angle-lever for rocking the shaft to release the teeth from the rack for returning the feed-carriage, substantially as set forth.

8. The combination with the feed-carriage 130 and means for controlling its movement, of a pulley, a cord connecting the periphery of the pulley with the carriage, a coiled spring for actuating the pulley and hence the carriage

a winding-wheel engaged with the spring for winding and unwinding the spring independent of the pulley and means for locking the winding-wheel to and releasing it from the 5 pulley, substantially as set forth.

9. The combination with the feed-carriage and means for controlling its movement, of a pulley fixed to rotate with a shaft, a cord connecting the periphery of the pulley with the 10 carriage, a pair of coiled springs for actuating the shaft and hence the carriage, winding-wheels for winding and unwinding the springs independent of the shaft and means for locking the winding-wheels to and releasing them 15 from the shaft, substantially as set forth.

10. In combination, a main supporting frame or pedestal, a support for the feed-carriage extending rearwardly from the main frame or pedestal, a pivoted bracket at the 20 rear of the feed-carriage support, wires stretched from the main frame to said pivoted bracket and forming a track for supporting the cards, means for actuating the feed-carriage and means for controlling its movement 25 substantially as set forth.

11. The combination with the punching and feeding mechanism and the means for operating them, of guide-checks mounted to slide toward and away from each other, a spring- 30 actuated lever, links connecting the lever with the checks to cause them to move simultaneously, a stop for limiting the movement of the lever and means for adjusting the stop, substantially as set forth.

12. The combination with the supports provided with elongated bearings, of a base-plate, means for adjusting the base-plate forward and backward on the bearings, a pattern-board hinged to the base and means for adjusting the pattern-board in different tilted 40 adjustments relative to the base, substantially as set forth.

13. The combination with the pattern-board and its support, of means for holding the pattern-board in various tilted adjustments 45 with respect to its support, a rule arranged to slide up and down along the face of the board and means for operating the rule whatever be the tilted adjustment of the pattern-board, substantially as set forth.

14. The combination with the card-feeding mechanism, the pattern-board and an indicator arranged to travel across the board and under the control of the feed mechanism and 55 means for tilting and bodily adjusting the pattern-board while the action of the indicator remains intact, substantially as set forth.

15. The combination with the pattern-board and a suitable support therefor, of a rule arranged to slide up and down along the face 60

of the board, a segment, a wire attached at its opposite ends to the segment, guide-pulleys at the back of the board for directing the wire up and down at each end of the board, connections between the wire and the movable rule and means for operating the segment to adjust the rule for reading the pattern, substantially as set forth. 65

16. The combination with the pattern-board, a suitable support therefor, a rule arranged to move up and down along the face of the board, a segment carried in rotary adjustment and a wire connecting the segment with the rule, of a worm and worm-wheel for operating the segment, a hand-lever for operating the segment and means for releasing the worm-wheel from the segment when the hand-lever is brought into use, substantially as set forth. 70

17. The combination with the pattern-board, a suitable support therefor, a rule arranged to move up and down along the face of the board and a rule-operating wire, of a segment, spring-actuated levers pivoted to the opposite ends of the segment and forming 85 bearings for the attachment of the ends of the wire and means for varying the tension of the wire, substantially as set forth. 80

18. The combination with the card-feeding mechanism, the pattern-board and a suitable support therefor, of an indicator mounted to travel across the face of the pattern-board and under the control of the feeding mechanism, and means for varying the extent of movement of the indicator at each step of feed, 90 substantially as set forth. 95

19. The combination with the pattern-board, a suitable support therefor and a rule arranged to move up and down along the face of the board, of an indicator mounted to move 100 bodily up and down with the rule, and means for imparting to the indicator a step-by-step movement across the face of the board, substantially as set forth.

20. The combination with the pattern-board, a suitable support therefor, and a double rule arranged to move up and down along the face of the board, a spring-actuated cord extending across the face of the board in two parts corresponding to the parts of the double rule, the said cord being mounted to move 105 bodily up and down with the double rule, and means for imparting to the cord a step-by-step movement across the face of the board, substantially as set forth. 110
